UNITED STATES PATENT OFFICE.

WILLIAM D. HONCHAN, OF CHICAGO, ILLINOIS.

WEIGHT GRADING-MACHINE.

1,224,379.

Specification of Letters Patent.

Patented May 1, 1917.

Application filed August 13, 1915. Serial No. 45,205.

To all whom it may concern:

Be it known that I, WILLIAM D. HONCHAN, a citizen of the United States of America, and a resident of Chicago, county 5 of Cook, and State of Illinois, have invented certain new and useful Improvements in Weight Grading-Machines, of which the following is a specification.

This invention relates to a machine for 10 grading or assorting articles by weight. In the embodiment of the invention shown in the drawings the machine is arranged for use in the packing industry for assorting comparatively large articles, such as hams, 15 etc.

The main objects of the invention are to 20 provide a machine of this class having a supporting table equipped with means adapted to be actuated by the weight of articles passing thereover for discharging them at various points along the table; to provide improved means for conveying articles along the table; and to provide an improved construction of trap door mechanism for assorting and delivering articles.

An illustrative embodiment of this invention is shown in the accompanying drawings, in which:

Figure 1 represents a side elevation of a 30 weight grading machine constructed according to this invention.

Fig. 2 is a sectional view taken on the line A—A of Fig. 1.

Fig. 3 is a detail of one of the carrying 35 plates of the conveyer.

The present invention is designed mainly to provide automatic and mechanically operative means for sorting by weight a considerable quantity of articles in a short time; 40 to avoid the necessity of manual selection and weighing of such articles; and to provide means for more accurately assorting such articles for the purpose of reducing the time required in curing; for instance, if inaccurately or unassorted hams 45 are cured together, it is usually found convenient to extend the curing operation for the lighter weight hams to the time required for curing the heavier hams. Thus the 50 present invention permits shortening of the time required in the curing process by from two to three weeks with certain weight of

hams, and also indirectly in more uniform curing.

Referring to the drawings, the machine 55 shown comprises a frame 1 having bearings at each end for supporting the shafts 2 and 3 on which are rigidly secured sprocket wheels 4 and 5. Also fixed on shaft 3 is a driving sprocket 6 by means of which power 60 is applied to the machine. Endless chains 7 driven by sprockets 4 and 5 have secured thereto at intervals along their length plates 8 which carry pivoted thereto resiliently mounted carrying plates 9. The motion of 65 plates 9 is limited in one direction by shoulders 10 on plates 8 and in the opposite direction is controlled by springs 11 extending between points 12 of plates 9 and spring supports 13 formed in plates 8. The purpose of 70 such resilient arrangement is to reduce the possibility of injury to articles conveyed.

The chain conveyer is guided by the guide members 14 and 15 secured to the upright members 16 supported by frame 1, the lower 75 set of guides 14 serving to maintain the carrying plates 9 at the desired height above table 17 supported by the frame 1.

The table 17 is provided with a plurality of openings 18 along its length, and fitting 80 within said openings are trap doors 19 pivot- ed in bearings 20 on frame 1 by the bars 21. The surfaces 22 of trap doors 19 are nor- mally flush with the surface of table 17, be- 85 ing normally held in such horizontal posi- tion by counterweights 23 adjustably mount- ed on the levers 24 fulcrumed on bolts 25 and depending bars 26. The levers 24 at their ends opposite the counterweights 23 have slots 27 through which pass bolts 28 90 mounted on depending arms 29 of the trap doors. This connection between levers 24 and arms 29 allows for eccentric pivotal movement between the levers 24 and the trap doors 19 around their respective fulcrums 25 95 and 21.

Slidably mounted in frame members 30 of the trap doors 19 are triggers or plungers 31 100 normally urged into position shown in the drawings by springs 32, and having their outward movement limited by pins 33 carried by said plungers. Pivotally mounted on bars 34 extending downwardly from table 17 are trip arms 35 in position for coöpera-

ing with the plungers 31 and being provided with adjustable counterweights 36 normally urging the arms 35 by gravity into the position shown in the drawings. The trips 35 and the plungers 31 have rounded ends at their point of contact, as shown in the drawings, in order that the plungers will be cammed inwardly and pass the ends of trips 35 when the corresponding trap doors are returned to the upper horizontal positions, under the gravity action of counterweights 23, after the selected articles are released from the trap doors. The triggers 35, therefore, normally serve to maintain the trap doors 19 in horizontal position, but when one of the trap doors carries a weight sufficient to overcome the action of the respective counterweight 36, the corresponding trigger 35 is rocked around its pivotal connection 37 on bar 34, disengaging the plunger 31 and permitting the corresponding trap door to rock downwardly, as appears in the center of Fig. 1. By this means an article delivered by the carrying plates 9 of the conveyer to a trap door which releases when carrying a weight equal to such article, is delivered to the appropriate chute or bin for articles of such weight.

In the operation of the device, assuming that the counterweights 36 are adjusted along their respective carrying arms or trips 35 to cause action of such triggers as required to size, assort, or release the heavier articles and then the lighter ones progressively, then, upon the operation of the machine, the articles being sorted are carried along the tables 17 from right to left (Fig. 1), the lighter articles will pass by the first trap doors without causing an operation thereof. When such lighter articles arrive on platforms arranged to be released at the corresponding weights, the pressure of the weight on such platforms causes the corresponding trips 35 to be rocked around their pivots 37 through the action of plunger 31 bearing on the ends of said trips. The trap door is in this manner released and rocked downwardly when it receives a weight sufficient to overcome the weight of the corresponding counterweights 36 and 23 as adjusted on their respective supporting levers 35 and 24. When the article slides off of the inclined trap door the latter is returned to its normal position by the weight of the counterweight 23.

Although but one specific embodiment of this invention has been herein shown and described, it will be understood that numerous details of the construction shown may be altered or omitted without departing from the spirit of this invention as defined by the following claims.

I claim:

1. In a machine of the class described, a

support, means for conveying articles placed on said support along the same, said support being provided with a plurality of openings therein, trap doors pivotally mounted on said support and normally closing said openings, counterweights arranged to urge said trap doors into closed position, trip devices for retaining said trap doors in a closed position, and adjustable means for causing said trip devices to release said trap doors when carrying different desired predetermined weights.

2. In a machine of the class described, a support, means for conveying articles placed on said support along the same, said support being provided with a plurality of openings therein, trap doors pivotally mounted on said support and normally closing said openings, counterweights arranged to urge said trap doors into closed position, trip devices for retaining said trap doors in a closed position, and counterweights adjustably mounted on said trips for causing said trip devices to release said trap doors when carrying different desired predetermined weights.

3. A machine of the class described, comprising a supporting structure having a surface or way for the passage of articles to be graded, an opening in said surface, a trap door normally closing said opening, a latch for retaining said door in closed position, and adjustable means for causing said latch to release the door on the application of a predetermined weight on said door.

4. A machine of the class described, comprising a supporting structure having a surface or way for the passage of articles to be graded, an opening in said surface, a trap door for closing said opening, means normally urging said door to closed position, a latch for retaining said door in closed position, and adjustable means for causing said latch to release the door on the application of a predetermined weight on said door.

5. In a device of the class described, a support, a trap door hinged to said support, means normally urging said door to closed position, and a latch for retaining said door in closed position, said latch being arranged to release the door on the application of a predetermined pressure on said door.

6. In a device of the class described, a support, a trap door hinged to said support, means normally urging said door to closed position, and a latch for retaining said door in closed position, said latch being adjustable for the purpose of releasing said door upon the application of a predetermined pressure on the door.

7. A weight grading machine, comprising a platform, a plurality of trap doors in said platform, means for conveying articles to be graded along said platform, said trap

doors being provided with spring pressed latch bolts, means for normally urging said trap doors to closed position, and counter-weighted levers pivoted to said platform and arranged to yieldingly engage said latch bolts whereby the trap doors are retained in closed position against the action of weights thereon until weights are applied

to the trap doors which are sufficient to overbalance said counterweighted levers. 10

Signed at Chicago this 7th day of August 1915.
